CLAIM

The ornamental design for a geometric wall basket, substantially, as shown and described.

DESCRIPTION

FIG. 1 is a front elevational view of a geometric wall basket showing my new design;

FIG. 2 is a rear elevational view thereof;

FIG. 3 is a side elevational view thereof, the opposite side view being a mirror image thereof;

FIG. 4 is a top view thereof; and,

FIG. 5 is a bottom view thereof.
